UNITED STATES PATENT OFFICE

2,652,245

MECHANISM FOR THE OPENING AND CLOSING OF WINDOWS, LOUVERS, OR THE LIKE

James Sydney Bentley, London, England, assignor to Teleflex Products Limited, London, England, a British company

Application April 24, 1951, Serial No. 222,670
In Great Britain April 24, 1950

5 Claims. (Cl. 268—21)

1

This invention relates to mechanism for the opening and closing of windows, louvers, shutters or the like in ventilating or heating systems, which turn upon a horizontal, vertical or other axis, and has for its object to provide such mechanism of great simplicity.

The mechanism with which the invention is concerned comprises a push-and-pull flexible metal cable of the type having a multi-stranded core with or without one or more compression-transmitting lays wound thereon and which has on its exterior single- or multi-start spaced helical projections, such cable being mounted in a fixed guiding conduit which can be rectilinear or curved, or comprise both rectilinear and curved portions and which is suitably secured in position.

According to the present invention the mechanism for the opening and closing of windows or the like comprises a cable of the type set forth in the preceding paragraph, connected by one end to a part movable with the window or the like in such manner that by exerting axial thrust or push on the suitably moved, positioned and guided cable, the window or the like is caused to open, the cable having a reverse movement by which the window or the like is caused or allowed to close.

The cable is connected to the frame or otherwise moving with the window or the like at a desired radial distance from the axis of turning and so that the connection comes adjacent or aligned with what may be termed the "mouth" of the guide or conduit when the window or the like is closed. This mouth and the neighbouring portion of the guide or conduit are so positioned and shaped that the cable "axis" at the point of connection is a "normal" to the plane of the movable window or the like. Thus, when the cable is given a thrusting or pushing movement the line of thrust on the movable window or the like is in the axis of the cable. As a result, the window or the like opens to the required angle and the portion of the cable between the window or the like and the mouth assumes a curved shape which is part or a substantial part of a circle.

It should be noted in any case that the cable should have such characteristics that for all openings of the window or the like up to the maximum it has the required rigidity and other necessary functional qualities not only to sustain the opening thrust but to act as a stay to support the window or the like in the opened position.

Where necessary, a window or the like may

have two cables for its operation, each of which is arranged as above set forth, and in a desired position the guiding means are run parallel to enable the parallel cables to be coupled by means of their helical projections.

The coupling means may be such that the main operating cable can cause the movement of another cable coupled thereto in the same direction by a toothed coupling slide engaging each cable, or in the same direction by two concentric gear wheels with the cables coming on the same side, or by a single gear wheel or coupled gear wheels in the reverse direction by the cables coming in diametrically opposite positions. In any case and whatever the exact layout, the extent of the coupling and/or re-coupling with cables coming in the same or reverse directions, is operated from the master cable moved by the operating means.

Any suitable means may be provided for effecting the movements of the cable, but preferably its helices are engaged by a handle-operated gear wheel (with or without reduction gear) having automatic clutch means of any suitable and known character for holding the parts locked in any adjusted position, between the limits of operation.

In order that the invention may be better understood, it will now be described with reference to the accompanying drawings, which are given by way of example only and in which:

Fig. 1 shows a somewhat diagrammatic perspective view of the elementary and primary means for carrying the invention into effect, which also shows a coupling means fitted thereto.

Fig. 2 shows a similar view to a smaller scale, illustrating the invention applied to a single window.

Fig. 3 shows a similar view to Fig. 2 but with the invention applied to two windows operated from a single master cable.

Fig. 4 shows a view similar to Figs. 2 and 3, showing the invention as applied to three windows operated from a master cable.

Fig. 5 shows in longitudinal section, and Fig. 6 in split plan, coupling means between a master cable and subordinate cable in which both cables are caused to move in the same direction.

Fig. 7 shows in elevation and Fig. 8 in sectional plan, an escutcheon plate for the connection of the ends of guiding conduits for the cable.

Fig. 9 shows a further diagrammatic perspective view illustrating a further method of carrying the invention into effect, whereby a master cable controls a plurality of subordinate cables.

Fig. 10 shows a cross sectional elevation of coupling means between a master cable and subordinate cable, whereby the latter moves in the reverse direction to the master cable.

Fig. 11 shows a similar view to Fig. 10 but where three subordinate cables can be controlled from a master cable.

Fig. 12 shows a plan view of Fig. 11, one-half being taken on the line 12—12.

Fig. 13 is a plan view of an installation utilising connectors such as shown in Fig. 10.

Fig. 14 shows an elevation of one connection in accordance with the system shown in Fig. 13.

Fig. 15 shows a similar view to Fig. 13, utilising the connectors as shown in Figs. 11 and 12.

Figs. 16 and 17 show elevations of the connecting means in accordance with the system shown in Fig. 15.

In the particular method of carrying the invention into effect shown in Figs. 1 and 2, the window 18 is mounted by its upper edge to turn upon a horizontal axis so that when closed its lower edge 19 comes against a corresponding fixed framework member. In the central position this fixed framework member 20 has one end of a guiding conduit 21 fixed thereto, preferably in the manner indicated in Fig. 8 hereafter referred to, so that on the exterior there is a circular mouth 22 which corresponds to the end of the guiding conduit. From this mouth 22, on the interior of the room, the guiding conduit lies in a horizontal plane and is given a somewhat semicircular bend 23, the radius of the bend being somewhat small although, of course, determined by the flexibility of the cable 24. Beyond this somewhat semicircular bend 23 the conduit has a reverse bend 25 and then runs horizontally along the fixed framework 20 to the end thereof where it is given a bend 26 in a vertical plane and then proceeds downwardly to the operating gear 27 which comprises, as before stated, a gear wheel and automatic clutch (not shown) and an operating handle 28. The cable 24 is of a size to slide readily in the conduit 21 and one end projects through the mouth 22 and is connected as shown in Fig. 1 to the framework 19 of the moving window 18. Towards the other end of the cable 24 meshes with the gear wheel (not shown) and below this the cable extends into the spent tube conduit 29 which is sufficiently long for the full travel of the cable.

It will be understood that from the closed position of the window 18, when the handle 28 is operated to open the window a thrust or pushing movement is given to the cable 24 which is axial to the cable and at right angles to the plane of the window 18 where the cable is connected to the frame 19 thereof. As a consequence, by the continued opening movement, this axial thrust causes the window 18 to be turned about its horizontal axis. The cable 24 is of sufficient stiffness and strength to hold the window 18 in any open position up to the maximum. To close the window 18, it is simply necessary to reverse the movement of the handle 28, when by the pull of the cable 24, assisted by the weight of the window, the closing movement is effected.

To distribute the effort and to enable two or more thrust points on windows, louvres, shutters or otherwise to be operated from a master cable, connecting means between the master cable and a subordinate cable or cables can be provided. Figs. 5 and 6 illustrate such a connecting means whereby the master cable causes a subordinate cable to move in the same direction. This con-

necting means, as illustrated, comprises two similar flat casing portions 30 and 31 which are united at their ends by screws 32. The casing portion 31 which comes lowermost has apertures 33 for securing screws. The complete casing has a somewhat flattened oval section and has such interior shaping when made up that it secures the flared ends 35 of guiding conduits therein. If desired and as shown, one unused outlet can be closed by a shaped plug 36.

The master cable 24 passes through the casing and in the mid position its helical projections engage a toothed slide 37 the teeth of which on one side are spaced suitably for the purpose. Similarly, a further set of teeth on the other side engages the helical projections of a subordinate cable 38. The dimensions of the parts and of the interior of the casing maintain the slide 37 in engagement with the cables whilst permitting the slide to have a reciprocating movement of the desired amount.

Thus, when the master cable 24 is moved it carries along with it and to a similar extent, the subordinate cable 38 which works in a conduit 39 fixed to one end of the casing.

Figs. 1 and 3 show an application of this device and from the latter it will be appreciated how two windows 40 and 41 (similar to the window 18) can be opened and closed from one master cable. Of course if desired the two windows 40 and 41 could be one large window to be operated by the two cables.

Obviously there are a great many structural arrangements which the devices described can take. In some, for example, there can be more than one subordinate cable, each of which can have its effective connection. Such an arrangement is shown in Fig. 4. In this figure the master cable controls a window 42 and subordinate cables windows 43 and 44; in this figure the arrangement of the connecting casings readily will be seen.

Where the direct thrust cable emerges from the fixed part, and at a right angle to the window, pivoted louvre, shutter, movable screen, or otherwise (according to the precise arrangement) it is connected to the window or the like in order that its thrust directly and without loss is applied thereto.

The general emerging mouth is as shown in Figs. 7 and 8 in which Fig. 7 shows an elevation of an escutcheon plate 32 fastened to the fixed support 45 from the rear by two screws 46. The plate 32 (Fig. 8) has a rear aperture coincident with that of the support. The extreme end 47 of the conduit 21 is held in the escutcheon plate by an encircling rubber packing ring or gasket 48. In the total result the end 47 of the conduit is held fixed and the cable 24 has a thrust normal to the window, louvre, shutter or otherwise for its opening.

Fig. 9 is an example where subordinate cables themselves become master cables, again to function as subordinate cables.

In this figure there are two windows pivoted midway on horizontal axes. At the two sides of each window, below its horizontal turning axis, there is a thrust cable connection.

The operation is from a main conduit and cable 24—24.

24 has a further connector 49 itself proceeding to a still further conduit and cable 50 for the operation of the upper window. Similarly, the subordinate conduit and cable 53 has another connector 51 operating a conduit and cable 52.

From the above it is quite obvious how with straight-running toothed connections between connectors as shown in Figs. 5 and 6 a multiplicity of co-operative cables can be utilised.

Further, in place of connecting two cables so that they can run together such as shown in Figs. 5 and 6, two cables can be connected together so that they run in opposite directions, yet to obtain similar results, that is to say, and as shown in Fig. 10, one cable 53, which can be the master cable, meshes with a gear wheel 54 on a spindle 55 in a two-part casing 56-57, so that another cable 58 carries on the work in an opposite direction.

In place of such a simple device as shown in Fig. 10, two gear wheels 59 and 60 having clutch engaging faces, may be engaged upon the spindle 55 with an upper part casing 56, a lower part casing 57 and two intermediate casing parts 61 and 62. In this last-mentioned case a main cable can turn one of the gear wheels, leaving another cable to be moved in the same direction as the main cable and one or two other cables to be moved in opposite directions.

Fig. 12 is a plan partly in section on the line 12-12, Fig. 11, which shows how the conduit, the ends of which are flared, are mounted in the parts of the assembly shown in Fig. 11 and how, from the master cable, the take-off can be to any desired grouping of one cable in the same direction and two cables in the opposite direction.

Advantage is taken of the structures such as shown in Figs. 10, 11 and 12 for movement from a master cable to be conveyed to a remote position or positions for the purposes of the invention.

Fig. 13 shows a diagrammatic cross-sectional plan in which cables are arranged such as shown in Fig. 10. In Fig. 13, which again it must be emphasised is a plan, 63 is the plan of the housings for the gears and 64 the plan of the conduit and master cable having supports 65 at spaced intervals.

The cable from the ultimate end 66 of the main conduit-cable assembly operates the window 67 which is on a vertical axis, and the other windows 68, 69 and 70 are operated through the subordinate conduit-cable assemblies 71-72-73 (the conduits and cables for which are but short).

Thus, from the main operating hand gear 74 all the windows are opened and closed with the aid of structures such as shown in Fig. 10.

An exemplification of the main structure utilised in Fig. 13 is shown in Fig. 14 which is an elevation. Here a bracket 75 is shown in connection with a fixed part 76 of the main framework of a building. This bracket supports a coupling means such as shown in Fig. 10 for the passage of the cables. The curved and bent conduit 77 passes from one of these positions to an escutcheon plate 78 supported by a bracket 79. Thus the cable 80 therefrom passes to the window structure 81 and by the hereinbefore described operation of the cable the window is opened and closed. It will be understood that the curved conduit 77 represents any one of the conduit and cable assemblies 71, 72 or 73.

Regarding Fig. 15, in this figure 82 is the hand-operated gear which operates a cable in a conduit 83 so that, in each desired position, a gear wheel structure 84 such as shown in Figs. 11 and 12, is operated. In other words, in the ultimate position to the left, at 85, the main cable in its conduit effects its particular purpose, and in the

same position the reverse action takes place through the coupled conduit and cable assembly 86.

In all the other positions there are two conduit and cable assemblies 87 and 88.

In the total result, in the whole of the positions 85-86 and in all of the positions 87-88 there is an outward thrust, more or less horizontal at the start and possibly curving upwards for turning the various windows and window structures about horizontal axes. The opening movements are indicated by the horizontal arrows, it being remembered that Fig. 15 is a plan.

Figs. 16 and 17, analysed, show how the mounting of the structures shown in Figs. 11 and 12 and indicated at 84 in Fig. 15, are arranged. Here the double gear wheel structure in its casing such as shown in Figs. 11 and 12 is mounted upon a fixed bracket 89 attached to the fixed part of the framework.

As will be seen from Fig. 16, there are four conduit positions and it will be understood that these can be utilised as hereinbefore particularly described so that a structure such as shown in Fig. 17 having a curved conduit portion 90 can represent either 85, 86, 87 or 88 such as hereinbefore set forth in connection with Fig. 15, in order that the cable moving therein can operate the window 91.

The invention is not limited to the precise forms or details of construction herein described, as these may be varied to suit particular requirements.

What I claim and desire to secure by Letters Patent of the United States of America is:

1. Mechanism for the opening and closing of windows, louvres, shutters or the like which turn upon an axis, and of the type operated by a flexible multi-stranded master cable having spaced helical projections formed on its exterior surface, said cable being reciprocally mounted in a fixed guiding conduit and supporting said cable so that its axis is substantially normal to the plane of the window, comprising connecting casing means through which the master cable and at least one similarly formed subordinate cable freely pass, said subordinate cable reciprocally mounted in a guiding conduit supporting said cable so that its axis is substantially normal to the plane of a window, and at least one toothed coupling member located within the casing means between the master cable and the subordinate cable to enable movements of the former cable to be imparted to the latter cable.

2. Mechanism for the opening and closing of windows, louvres, shutters or the like which turn upon an axis, as claimed in claim 1, in which the connecting casing means consists of a pair of semi-circular portions, fastening means for securing the casing portions together with their concave faces adjacent each other, and the toothed coupling member consists of a slide, said slide having a set of teeth formed on one side thereof to engage the helical projections of the master cable, and another set of teeth formed on the opposite side thereof to engage the helical projections of the subordinate cable so that rectilinear movement of the former cable in one direction will impart a rectilinear movement to the slide strip and the latter cable in the same direction.

3. Mechanism for the opening and closing of windows, louvres, shutters or the like which turn upon an axis, as claimed in claim 1, in which the connecting casing means consists of a pair

of semi-circular portions, fastening means for securing the casing portions together with their concave faces adjacent each other, grooved locking means formed in the ends of the casing portions to retain flared ends of the guiding conduits when said casing portions are secured together, and the toothed coupling member consists of a slide, said slide having a set of teeth formed on one side thereof to engage the helical projections of the master cable, and another set of teeth formed on the opposite side thereof to engage the helical projections of the subordinate cable so that rectilinear movement of the former cable in one direction will impart a rectilinear movement to the slide strip and the latter cable in the same direction.

4. Mechanism for the opening and closing of windows, louvres, shutters or the like which turn upon an axis, as claimed in claim 1, in which the connecting casing means consists of a pair of semi-circular portions, fastening means for securing the casing portions together with their concave faces adjacent each other, and the toothed coupling member consists of a gear wheel, a spindle located transversely of the connecting casing means on which said gear is rotatably mounted so that teeth on one side thereof engage the helical projections of the master cable and teeth on the diametrically opposite side of the gear engage the helical projections of the subordinate cable enabling rotational movement of the master cable to move said cable rectilinearly in one direction and impart a rotational

movement to the gear to move the subordinate cable rectilinearly in the opposite direction.

5. Mechanism for the opening and closing of windows, louvres, shutters or the like which turn upon an axis, as claimed in claim 1, in which the connecting casing means consists of a pair of semi-circular portions, fastening means for securing the casing portions together with their concave faces adjacent each other, and the toothed coupling member consists of two gear wheels, clutch engaging facings formed on the adjacent faces of the gears, a spindle located transversely of the connecting casing means on which said gears are rotatably mounted so that the teeth on diametrically opposite sides thereof engage the helical projections of the master cable and the helical projections of three subordinate cables, one of which is moved rectilinearly in the same direction as the master cable and the other two moved rectilinearly in the opposite direction thereto when said master cable is rotated.

JAMES SYDNEY BENTLEY.
